UNITED STATES PATENT OFFICE.

FRANK TYLER, OF EAST HIGHLANDS, CALIFORNIA.

PAPER-HOLDER.

1,265,553.

Specification of Letters Patent.

Patented May 7, 1918.

Application filed June 16, 1917. Serial No. 175,070.

To all whom it may concern:

Be it known that I, FRANK TYLER, a citizen of the United States, residing at East Highlands, in the county of San Bernardino 5 and State of California, have invented new and useful Improvements in Paper-Holders, of which the following is a specification.

This invention relates to a paper holder adapted to hold sheets of thin paper. It is 10 common practice to wrap fruit with tissue-paper. Holders have been provided to maintain the paper in piles convenient for the wrappers, so that a sheet at a time may be quickly and conveniently removed from 15 the holder.

My invention pertains particularly to a holder, which has a needle for holding the sheets, the needle piercing a few of the upper sheets of a pile. The construction is 20 such that the needle follows the pile as it diminishes in height, and each sheet must be torn from the needle grip.

It is an object of my invention to provide a holder of the character described, which 25 has a needle feeding downwardly in a straight line.

It is a further object of my invention to provide details of structure, whereby a strong holder may be secured, and whereby 30 simplicity of structure and ease of operation are obtained.

I accomplish these objects by means of the embodiment of my invention illustrated in the accompanying drawing, in which:—

35 Figure 1 is an isometric view of a packing box, with a paper holding board disposed thereon. Fig. 2 is an enlarged side view of the paper holder, with the board shown in section. Fig. 3 is a front view of the holder 40 with a fragment of the board shown.

Referring particularly to Fig. 1, A indicates a packing box having two compartments, such as is used for packing oranges. The compartment B is in position for packing 45 the wrapped oranges therein, and the board covers compartment C. The board is indicated by D, and the paper holder E is secured to one wall of the board. The board comprises a bottom which covers compartment C and upstanding from the bottom are side walls. The holder E is secured to the 50 wall 4 and is shown in detail in Figs. 2 and 3.

The holder comprises a bracket 5, which 55 preferably consists of a single strip of metal

bent into a loop with the ends of the strip serving as jaws of a clamp. Apertures are provided in the front and rear of the bracket, and extending therethrough is a clamping bolt 6, the head thereof being disposed at the rear and the threaded end at the front of the bracket. A wing nut 7 is disposed upon the threaded end of the bolt 6, and engages the front of the bracket. The wall 4 is placed in position between the jaws of the bracket, and the wing nut tightened to firmly secure the bracket to the wall 4. Registering apertures are provided in the bracket at the top and bottom thereof. Slidingly mounted in the last named apertures is a needle bar 8. The upper end of needle bar 8 is bent forwardly as indicated at 9 to provide a finger hold, whereby the bar may be lifted. The bottom of the needle bar is off-set as indicated by 10, and the end 70 thereof threaded. A collar 11 is fixedly secured to the off-set portion 10. A nut 12 is mounted upon the threaded off-set 10, and a needle 14 is clamped between the nut and collar 11. This provides means for renewing 75 the needle in the case of breakage. A spring 15 serves to project the needle bar. The spring 15 is herein shown formed of a steel spring wire having one end formed 80 with an eye 16 through which the bolt 6 extends, and having a loop at the center. The other end 17 has a bend therein, and is hooked over the off-set 10. In order to hold the spring in place on the bolt 6, a coil 85 spring 18 is disposed on the bolt in position 90 to hold the eye between the front wall of the bracket and the end of the spring.

A pile of paper F is disposed on the bottom wall of the paper board, and the needle 14 allowed to pierce the upper sheets of the 95 pile of paper. The packer removes one sheet at a time by tearing the sheets from the needle. Due to the fact that there is no pressure upon the upper sheets of the pile, there is no tendency to pull more than one 100 sheet at a time from the pile.

What I claim is:—

In a paper holder the combination of a bracket comprising a finger adapted to engage the rear face of a supporting wall and 105 a loop projecting forward of said finger having the end thereof adapted to engage the front face of said wall, a tightening member for compressing said loop to grip said wall, said tightening member having its ad- 110

justment head disposed at the front of said loop, a needle bar slidably secured in said bracket for straight line movement, said bar having an offset portion at the bottom, a torsion spring having one end thereof bearing upon said tightening member and one end upon the offset portion of said bar tending to project the same, the free end of said

offset portion being threaded, and means mounted on said threaded end for removably confining a needle.

In witness that I claim the foregoing, I have hereunto subscribed my name, this 11th day of June, 1917.

FRANK TYLER.
